INVENTOR:

Fredewett Jewett

UNITED STATES PATENT OFFICE.

FREDERIC A. JEWETT, OF GRAFTON, MASSACHUSETTS, ASSIGNOR OF ONE-HALF TO CHARLES L. LEONARD, OF SAME PLACE.

HORSE AND CATTLE CLEANER.

SPECIFICATION forming part of Letters Patent No. 354,145, dated December 14, 1886.

Application filed July 1, 1886. Serial No. 206,767. (No model.)

To all whom it may concern:

Be it known that I, FREDERIC A. JEWETT, of Grafton, in the county of Worcester and Commonwealth of Massachusetts, have invented certain new and useful Improvements in Horse and Cattle Cleaners; and I do hereby declare that the following is a full, clear, and exact description of the same, reference being had to the accompanying drawings, forming a part of this specification, and in which—

Figure 1 represents a vertical central section through the cleaner and its handle on line $x\ x$, Fig. 2; and Fig. 2 represents a bottom view of the completed device, showing the form and arrangement of the cleaning devices, as will be hereinafter described.

To enable those skilled in the art to which my invention belongs to construct and use the same, I will proceed to describe the same in detail.

My invention consists in the combination, with a back provided with a suitable handle, of a series of endless corrugated cleaners arranged in concentric circles on the working-face of the back or part opposite to which the handle is attached, as will be hereinafter described.

In the drawings, the part marked A is the back or frame part, to which the handle or strap B is fastened by means of rivets C. In this instance the handle B, is leather, and three rivets, C, are used on each end to fasten its ends D D to the metal back part A. I prefer to make the back or frame part A from tin or sheet metal, and to stamp or press it out in a suitable mold, so as to form the back A and the outer course of cleaning-corrugations, E, in a single piece, as indicated in the drawings, while the inner courses, E, are made from tin

or sheet-metal strips corrugated and bent into the proper form, with the ends lapped and then their upper edges, a, soldered to the under side of the back part A.

It will be understood that any desired number of endless courses of corrugated cleaners E may be employed, and that, if desired, all the courses E may be made from tin or sheet-metal strips and then soldered to the under side of the back A; or, still again, the inner courses may be stamped or pressed out with backs, same as outer course in this instance, and then placed in position, and all the backs riveted or otherwise securely fastened together.

It will be observed that the edges b of the cleaners E are made without teeth, and that sharp corners are not found, thereby obviating all the difficulties and objections resulting from cleaners heretofore in use wherein teeth and sharp corners are found.

Having described my improved horse and cattle cleaner, what I claim therein as new, and desire to secure by Letters Patent, is—

1. An improved horse and cattle cleaner consisting of a rigid horizontal metal back or frame, A, provided with a handle or holding-strap, B, upon its upper side, and a series of continuous corrugated smooth-edged cleaners, E, of different sizes, secured to its under side and relatively arranged, as and for the purposes set forth.

2. The combination, with a back piece provided with a handle, of a series of comb-bars secured to the back piece and provided with corrugations, for the purposes set forth.

FREDERIC A. JEWETT.
